AUTOMATIC MECHANISM FOR CARBINES

Ross Rudd, Springfield, Mass.

Application February 27, 1947, Serial No. 731,199

3 Claims. (Cl. 89—141)

(Granted under the act of March 3, 1883, as
amended April 30, 1928; 370 O. G. 757)

1

The invention described in the following specification and claims may be manufactured and used by or for the Government for governmental purposes without the payment to me of any royalty thereon.

This invention relates to a new and useful mechanism for automatic operation of carbines and is particularly designed to modify a carbine, cal. .30 whereby it can be fired either full automatic or semi-automatic. The device is very simple in construction and operation, comprising only few parts which are readily fabricated and attached by making very slight changes in the firing mechanism of the carbine. One of the most important advantages of the device is that all carbines already in use can be easily and quickly converted with no major changes in the standard mechanism. The modified gun contains only two additional operating parts, a cam plate and a trigger bar, both of which are made from flat material suitable for easy and rapid production. The other parts are a stud, springs and pins of ordinary types. The only modification of the firing mechanism is bores for the stud and pins, and slots for the plate and bar.

The cam plate is pivoted in the trigger to operate the sear, for automatic firing. The trigger bar is mounted on the trigger housing for operating the cam plate. The stud is adjustable on the operating slide of the carbine for operating the trigger bar automatically by action of the slide.

The device is so designed that it can be applied to the carbine and then rendered operative for full automatic fire or rendered inoperative for semi-automatic fire. The two conditions of the device depend merely on the adjustment of the stud relative to the operating slide. When the device is inoperative, the firing mechanism functions for semi-automatic fire in its normal manner unaffected by the attached device. It is obvious therefore that any failure of the device will not affect the semi-automatic operation of the carbine, which is one of the distinct advantages of the device.

While one specific embodiment of the invention is illustrated in the drawings and herein-after fully described, it is to be distinctly understood that the invention is not considered to be limited to said specific embodiment but that its scope is defined by the claims appended hereto.

In the drawings:

Figure 1 is a side elevation of the firing mechanism of a carbine equipped with the device, the

parts being in normal position for semi-automatic operation;

Figure 2 is a longitudinal, axial, vertical section of the mechanism shown in Figure 1;

5 Figure 3 is a fragmentary section of trigger, sear and hammer of Figure 2, the parts being in cocked position, for semi-automatic operation;

Figure 4 is a view similar to Figure 3, the parts being cocked for automatic operation;

10 Figure 5 is a view similar to Figure 2, showing the automatic operation releasing the hammer from its position in Figure 4, for firing;

Figure 6 is a perspective view of the device associated with the trigger, sear, hammer and fragment of the operating slide;

15 Figure 7 is a longitudinal vertical section of the trigger;

Figure 8 is a perspective view of the cam plate of the device for the automatic operation of the sear;

20 Figure 9 is a fragmentary side elevation of the modified operating slide, partly in section.

As illustrated in the drawings, the device is applied to a U. S. carbine, cal. .30 having the 25 firing mechanism comprising the operating slide 1 retracted by gas pressure and returned on counter-recoil by its spring (not shown), the bolt 2 with firing pin 3, and hammer 4 pivoted in the trigger housing 5 with trigger 6 and sear 7 also pivoted therein. The sear 7 is disposed between ears 8 on the upper edge of the trigger 6. A pintle pin 9, received through ears 8 of trigger 6 and an elongated slot 10 in sear 7 and mounted in housing 5, pivotally mounts trigger 6 in housing 5, and sear 7 in trigger 6. A sear spring 11 is seated in trigger 6, bears against depending lug 12 disposed on the bottom of sear 7 below slot 10, and biases sear 7 forwardly on pin 9, the forward arm 13 of sear 7 being urged upwardly. Trigger 6 has in its upper, rear face a slot 14 on each side of which are sockets 15, respectively, to receive the ends of the trigger spring 16 mounted in housing 5 and biasing trigger 6 forwardly into inoperative position. Trigger 6 has a forwardly

35 projected safety nose 17 co-acting with a sliding safety bolt 18 in housing 5 and having a slot 19 into which nose 17 is received when the safety bolt 18 is oscillated to permit firing. Trigger 6 has a shoulder 20 on its rear face co-acting with housing 5 to limit rearward movement of trigger 6. Trigger 6 has a pair of upstanding ears 21 to co-act with rear arm 22 of sear 7 for semi-automatic operation. The hammer 4 is pivoted on pintle pin 23 mounted in housing 5 so that when 40

45 its head 24 is swung forwardly it co-acts with 45

50 housing 5 to limit rearward movement of trigger 6. Trigger 6 has a pair of upstanding ears 21 to co-act with rear arm 22 of sear 7 for semi-automatic operation. The hammer 4 is pivoted on pintle pin 23 mounted in housing 5 so that when 55 its head 24 is swung forwardly it co-acts with

firing pin 3 when bolt 2 is in battery. Head 24 has a cam shoulder 25 co-acting with bolt 2 to swing head 24 rearwardly to cock hammer 4. Hammer 4 has a convex bottom edge 26 against which forward arm 13 of sear 7 bears, and a notch 27 at the rear end of edge 26 into which the outer end of forward arm 13 is received when the hammer 4 is cocked. Hammer 4 has an operating plunger 28 mounted in the housing 5 and urged forwardly by the hammer spring 28', to cause head 24 to impinge against firing pin 3 when hammer 4 is released from sear 7.

The improved device, by which the above described details of construction are modified for automatic operation, comprises an operating cam plate 29 for actuating sear 7 to release hammer 4, a trigger bar 30 for actuating the plate 29, a selector stud 31 for actuating the trigger bar 30 and a stop-pin 32 for limiting movement of plate 29.

The plate 29 is disposed in slot 14 of trigger 6, being pivoted in trigger 6 by pintle pin 33 in trigger 6. Plate 29 has a cam shoulder 34 co-acting with rear arm 22 of sear 7, and a head 35 projected upwardly at the rear of plate 29. The trigger bar 30 is slidably mounted on housing 5 by means of a headed pin 36, the shank of which passes through an elongated slot 37 in the said bar and is welded to the trigger housing 5. Bar 30 has on its rear end an operating finger 38 received in a slot 39 in housing 5 and co-acting with head 35 of plate 29 to rock plate 29 forwardly when bar 30 is oscillated forwardly. Bar 30 has on its front end an upwardly extended operating post 40 with which co-acts the selector stud 31 which is vertically slidable in the rear end of the operating slide 1. As clearly shown in Fig. 9, the stud 31 is received in a suitable bore 41 in slide 1, with depressions 42 for spring pressed button 43 for retaining stud 31 in adjusted positions. Stud 31 is mounted in slide 1 immediately adjacent retracting handle 44 for manual movement of slide 1. It will be understood (Fig. 6) that when stud 31 is depressed to extend below slide 1 it engages post 40 to slide bar 30 forwardly, and that when stud 31 is raised to extend above slide 1 by placing a finger under the stud and pressing it upward (Fig. 1) the stud 31 passes above the top of post 40. The trigger bar 30 has a shoulder 45 against which bears an expansion spring 46 mounted in housing 5 for sliding bar 30 rearwardly when spring 45 is tensioned by forward movement of bar 30. Pin 32 is mounted in housing 5 rearwardly of plate 29 to limit rearward movement of plate 29 to properly relate head 35 of plate 29 and finger 38 of bar 30.

From the foregoing description of the details of construction of the device and its application to the firing mechanism of the carbine, its use and operation will be obvious. Figures 1, 2 and 3 show the device in inoperative position, thereby conditioning the carbine for semi-automatic operation. To render the device inoperative the selector stud 31 is raised (Fig. 1). The parts being as shown in Figure 2 (normal position), the operating slide 1 is retracted by pulling the retracting handle 44, thereby retracting bolt 2 to cock hammer 4, feed a round from the magazine into loading position, and tension the spring of slide 1. When the slide 1 is released, its spring projects the slide 1 and bolt 2 to battery, chambering the round. As shown in Figure 3, the sear 7 having its forward end 13 seated in notch 27 of hammer 4 is retracted on pin 9 by the force 75

of the tensioned hammer spring 28' superior to that of sear spring 11, its rear arm 22 being disposed on top of ears 21 which are depressed by trigger 6 disposed forwardly in inoperative position. When safety bolt 18 is shifted to permit nose 17 to enter slot 19, the carbine can be fired. When trigger 6 is squeezed, it rocks on pin 9 to raise ears 21 which raise arm 22 to rock sear 7 releasing hammer 4 which functions to fire the chambered round. The recoil of slide 1 and bolt 2, ejects the case of the fired round, cocks hammer 4, and feeds the second round to loading position. Counter recoil chambers the second round and brings the slide 1 and bolt 2 to battery, and the carbine is conditioned to be re-fired by trigger 6 which, released after first round was fired, has returned to normal inoperative position. It will be noted (Figs. 2, 3 and 4) that during the above-described operations, finger 38 is held fully retracted and plate 29 is slidably supported by stop-pin 32, and has no part in the semi-automatic operation.

Figures 4, 5 and 6 show the device in operative position thereby conditioning the carbine for automatic operation. To render the device operative, the selector stud 31 is depressed (Figs. 5 and 6). The first round is fired, as above described. The trigger 6 is not released but held retracted as shown in Figure 4. As above described, recoil ejects the case of the fired round, cocks hammer 4 and feeds the second round to loading position. It will be noted (Fig. 4) that when hammer 4 is cocked the rear arm 22 is moved against ears 21 in line with arm 22 and not below as previously described. Sear spring 11 urging arm 13 of sear 7 upwardly maintains hammer 4 cocked. Counter recoil chambers the second round and brings slide 1 and bolt 2 to battery. After the mechanism for rotating bolt 2 for locking has functioned, slide 1 moves forwardly sufficiently (Fig. 5) to cause stud 31 to engage post 40 and slide trigger bar 30 forwardly, thereby drawing finger 38 against head 35, rocking plate 29 which was raised by retraction of the trigger to press shoulder 34 against arm 22 of sear 7 releasing hammer 4 which fires the second round. It is obvious that this automatic operation continues until the magazine is exhausted or the trigger 6 is released to lower plate 29 and ears 21 thereby moving head 35 of plate 29 out of the path of finger 38 (Fig. 3).

From the foregoing description of the operation of a carbine equipped with the improved device, it is obvious that the structural elements, whereby full automatic operation is provided, can be incorporated in the firing mechanism of the carbine in such a manner as to dispense with any adjustability, to produce a carbine designed for full automatic fire only. This can be done by merely mounting stud 31 non-adjustably on the slide 1, as by making it integral therewith.

Having described the invention, what I claim is:

1. In an attachment for the firing mechanism of a gun whereby said mechanism can be operated alternatively for semi-automatic and full automatic fire, said mechanism comprising a trigger housing, a trigger pivoted in said housing, a hammer pivoted in said housing, a sear pivoted in said trigger for holding said hammer cocked, a slidably bolt having a firing pin therein, and an operating slide for sliding said bolt, reciprocable on recoil and counter-recoil, the combination of a cam plate pivoted in said housing and having a cam shoulder and an upstanding head; a trig-

ger bar slidably mounted on said housing, having an operating finger on its rear end and a post on its forward end, and spring-biased rearwardly; and a stud adjustably mounted in said operating slide for operative and inoperative positions to condition the mechanism for full automatic and semi-automatic fire, respectively, the parts being so related that the hammer is cocked by the bolt on recoil of said slide, and when said stud is adjusted to inoperative position, for semi-automatic fire, the cocked hammer is released to impinge against said firing pin by releasing the sear by squeezing the trigger, and that, when said stud is adjusted to operative position for full automatic fire, on counter-recoil of said slide the stud contacts said post, sliding said bar forwardly, the forwardly moving finger of said bar, contacting said head of said cam plate, rocks said plate, said cam shoulder of the plate rocks the sear, and said hammer is released to impinge against said firing pin.

2. In the firing mechanism of a gun operable alternatively for full automatic and semi-automatic fire, the combination of sliding operating means retracted on recoil and projected on counter-recoil; spring-pressed percussion firing means cocked by said operating means on recoil; a pivoted detent for engaging said firing means; a manually operated pivoted lever for rocking said detent to release said cocked firing means; a second pivoted lever for rocking said detent to release said cocked firing means; a sliding member for rocking said second pivoted lever; and a second sliding member on said operating means, manually movable alternatively into operative and inoperative positions to condition the mechanism for full automatic and semi-automatic fire, respectively, and for sliding said first sliding member when said second sliding member is in operative position and said operating means is projected on counter-recoil.

3. In a gun, operable alternatively for full auto-

matic and semi-automatic fire, the combination of a trigger housing; a trigger pivoted in said housing; a hammer pivoted in said housing; a sear pivoted in said trigger, for holding said hammer cocked; a slideable bolt having a firing pin therein; an operating slide for sliding said bolt, reciprocable on recoil and counter-recoil; a cam plate pivoted in said trigger and having a cam shoulder and an upstanding head; a trigger bar slidably mounted on said housing, having an operating finger on its rear end and a post on its forward end; and spring-biased rearwardly; and a stud adjustably mounted in said operating slide for operative and inoperative positions to condition the gun for full automatic and semi-automatic fire, respectively, the parts being so related that the hammer is cocked by the bolt on recoil of said slide, and when said stud is adjusted to inoperative position for semi-automatic fire, the cocked hammer is released to impinge against said firing pin by releasing the sear by squeezing the trigger, and that when said stud is adjusted to operative position, for full automatic fire, on counter-recoil of said slide the stud contacts said post, sliding said bar forwardly, the forwardly moving finger of said bar, contacting said head of said cam plate, rocks said plate, said cam shoulder of the plate rocks the sear, and said hammer is released to impinge against said firing pin.
